UNITED STATES PATENT OFFICE.

MILFARD W. BOYCE, OF KEARNEY, NEW JERSEY.

LOCKING DEVICE FOR AUTOMOBILES.

1,211,064.

Specification of Letters Patent. Patented Jan. 2, 1917.

Application filed December 1, 1915. Serial No. 64,442.

To all whom it may concern:

Be it known that I, MILFARD W. BOYCE, a subject of the King of England, residing in the town of Kearney, in the county of Hudson and State of New Jersey, have invented certain new and useful improvements in Locking Devices for Automobiles, of which the following is a full, clear, and exact description, such as will enable others skilled in the art to which it pertains to make, construct, and use the same, reference being had to the accompanying drawings, and to numerals of reference marked thereon, forming a part of this specification.

15 My invention relates to a locking device, especially designed for locking the controlling lever of any style of automobile from motion, so as to prevent the automobile from being operated by an unauthorized person, 20 as well as to prevent the theft of the machine.

The object of this invention is the production of a locking device which shall be simple in construction, durable in use, comparatively inexpensive in cost, consisting preferably of a base plate adapted to be secured to the floor of a car adjacent to the lever, and mounting upon said base plate a standard which can be adjusted toward or away from 30 said lever, said standard supporting a pivoted locking arm, which is provided with means for interlocking engagement with said lever.

With this end in view, my invention consists in certain novelties of construction and arrangement of parts, as hereinafter set forth and pointed out in the claims.

While the preferred form of my invention is illustrated in the accompanying drawings, 40 yet it is to be understood that minor detail changes may be made without departing from the scope thereof.

In the accompanying drawings, Figure 1 represents a side elevation, showing the application of the invention for holding a control lever locked against movement. Fig. 2 represents a plan view thereof. Fig. 3 represents an enlarged, fragmentary side elevation of the free end of the locking arm, just 50 before the recess in the locking arm engages with the stud on the back of the operating lever, and before the latch bolt of the lock on the locking arm engages with the latch bolt receiving element on the operating lever. Fig. 4 represents a similar view, showing the parts in locked position; and Fig. 5

represents an end view, partly in section, taken on lines $x-x$ of Fig. 2, and looking in the direction indicated by the arrow.

Similar numerals of reference refer to like parts throughout the specification and drawings.

In the drawings, the numeral 1 represents an attaching base plate provided with suitable slots for the passage of fastening devices, as for instance, bolts 2, by means of which the standard 3 is adjustably secured to said base plate. The base plate may be secured to the bottom of the car in any convenient or desired manner. The upper end 70 of the standard 3 is slotted and provided with alined apertures, by means of which one end of the locking arm 4 is pivotally secured thereto by means of the headed stud 5. The lower end of the standard 3 is provided with a suitable base 14, said base being provided with suitable apertures to receive the threaded portions of the bolts 2, and by means of which and suitable nuts, the standard may be adjustably secured to 80 the base plate 1. The free end of the arm 4 is provided with a recess 6, designed to have holding engagement with a stud 7 secured to one side of the operating lever 8 in any convenient and desired manner, and by 85 means of which the arm 4 has holding engagement with the operating lever 8. Secured to one side of the arm 4 at its free end, is a lock case 9, preferably of the pin-cylinder type, and secured to the operating lever 90 90 is a latch bolt receiving element 10, adapted to receive the latch bolt 11 of said lock, and by means of which the arm 4 is positively locked to the operating lever 8, as clearly indicated in the different views of 95 the drawings.

Although I have shown in the drawings the latch bolt receiving element 10 secured to the face of the operating lever 8, it is to be understood that for convenience sake, the 100 same may be secured to the opposite side of the lever to which the stud 7 is secured.

By means of the slots formed in the base plate 1, the standard may be adjusted so as to dispose the same at different distances 105 from the operating lever 8 for effective engagement of the holding and locking means, if for obvious reasons the distance from the end of the standard 3 and the operating lever 8 should vary. When the device is not 110 in use, the locking arm 4 may be swung upward into engagement with a suitable

spring-clasping member 12 secured to the car at any convenient point and with which it has frictional engagement, as clearly indicated in the dotted lines in Fig. 1 of the drawings.

In the operation of this mechanism, the operating lever 8 is locked by swinging the arm 4 from the position shown in dotted lines into the position shown in full lines 10 in Fig. 1 of the drawings, which operation simultaneously causes the recess 6 of the locking arm to engage with the stud 7 on the lever 8, and permits the latch bolt 11 of the lock 9 to automatically enter into locking engagement with the latch bolt receiving element 10. When it is desired to use the machine which is locked by this mechanism, the operator by means of a key (not shown), releases the latch bolt 11 from locking engagement with the latch bolt receiving element 10, and the arm 4 is then free to be swung upward into engagement with said spring-clasping member 12, which maintains said arm 4 out of operating position until again needed.

It will be understood that the construction and arrangement and combination of the parts above shown, are given only to illustrate the practical embodiment of my invention; and experience has demonstrated that the same is a highly efficient device, but it is obvious that minor variations thereof, not involving the exercise of invention, may be made by any skilled mechanic, and such departures from what is herein described and claimed, not involving invention, I consider within the scope and terms of my claims.

Having thus described my invention, what 40 I desire to claim is:

1. In a device for securing an operating lever, a base plate provided with slots secured to the floor of a car, a standard de-

signed to be adjustably secured in said base plate by means of said slots toward and 45 away from the operating lever, an arm pivotally secured to said standard, the free outer end of said arm being provided with a recess, a stud secured on said operating lever adapted to be engaged by the recess 50 in said movable arm, pin-cylinder means secured on said movable arm, a keeper on said operating lever in close proximity to said stud, said pin-cylinder means adapted to engage with said keeper, whereby when 55 said means are in locking engagement with said keeper, said stud and recess are in further engagement, for locking and holding said operating lever in its normal position.

2. In a device for securing an operating lever, an adjustable standard, an arm pivoted to said standard adapted to be engaged by and disengaged from the operating lever, the free outer end of said arm being provided with receiving means, holding means 65 secured on said operating lever designed to engage with the said receiving means on said movable arm, pin cylinder means also secured on the free outer end of said movable arm, a keeper on said operating lever in close proximity to the means on said operating lever, said pin-cylinder means adapted to engage with said keeper, whereby when said means are in locking engagement 70 with said keeper, the first-mentioned means 75 on both the movable arm and operating lever are also in engagement, for locking and holding said operating lever in its normal position.

This specification signed and witnessed, 80 this 29th day of November, 1915.

MILFARD W. BOYCE.
